UNITED STATES PATENT OFFICE.

ABRAHAM NEWMAN, OF BROOKLYN, NEW YORK.

NON-INTERFERENCE ELECTRICAL SIGNALING APPARATUS.

SPECIFICATION forming part of Letters Patent No. 449,690, dated April 7, 1891.

Application filed February 28, 1890. Serial No. 342,127. (No model.)

To all whom it may concern:

Be it known that I, ABRAHAM NEWMAN, of Brooklyn, in Kings county and the State of New York, have invented a certain new and 5 useful Improvement in Non-Interference Electrical Signaling Apparatus, of which the following is a specification.

I will describe the improvement in detail, and then point out the novel features in 10 claims.

In the accompanying drawings, Figure 1 is a face view of a signal-box. Fig. 2 is a sectional elevation of the same, taken through the plane of the line xx , Fig. 1. Fig. 2* is a 15 view of parts of an apparatus of a signal-box embodying my improvement. Fig. 3 is a detail view of parts of the apparatus of the signal-box. Fig. 4 is a view shewing other parts of the apparatus. Fig. 5 is a face view of an 20 apparatus at a central station or office. Fig. 6 is a plan view of the mechanism of said central-station apparatus. Fig. 7 is a side view of said mechanism. Fig. 8 is a detail view of certain parts of said mechanism, and Fig. 9 25 is a diagram showing the connection of signal-boxes with apparatus arranged at a central station or office.

Similar letters of reference designate corresponding parts in all the figures.

30 I will first describe the apparatus of the signal-box.

A designates a shaft, to the upper end of which is fastened a circular plate B. This plate has a knob b fastened to it, and a lug b', which serves also as an index, is also fastened on this plate. A pin a is fastened on the shaft A, and is long enough to strike against the pin a' fastened to the frame. The rotation of the shaft A past the point where those 35 two pins strike each other is thus prevented, and the index of the signal-box is so arranged that when the pins a and a' rest against each other said index points to zero. To the shaft A is also fastened a ratchet-wheel C, and below this ratchet-wheel is a toothed wheel D, upon which is arranged a pawl d, held in contact with the teeth of the ratchet-wheel C by a spring in the ordinary manner. The shaft A passes through the toothed wheel D, but is 45 not fastened to it. The toothed wheel D meshes with another wheel in a manner well known in clock-movements, and this wheel is

50 prevented from too rapid rotation by the verge F. Below the toothed wheel D and fastened to it is another ratchet-wheel G, and in contact with the teeth of this ratchet-wheel is a pawl g, which is mounted at one end to a portion of the frame.

To the ratchet-wheel G is fastened another wheel H, and underneath the wheel H is a 60 spring I, coiled around the shaft A and having one of its ends attached to said shaft, while the other end is fastened to one of the posts of the frame. Excepting where non-conducting material is required, the various 65 parts of the movements of the signal-box will preferably be made of conducting material.

J J' designate a pair of spool-magnets suitably mounted and having their cores connected in the usual manner. The armature J² of these magnets is fastened to an arm J³, one end of which is fastened by a pin to standards j j. A pin j² plays within a slot formed in the other end of said arm J³. The pin j² is fastened to arms j³ of a plate j⁴. The 75 arms of this plate j⁴ are pivoted in suitable bearings j⁵, and a spring, as j⁶, presses against the pin j², and thus the armature J² is normally held away from contact with the magnets J J'. 80

The mechanism hereinbefore described is inclosed in a suitable case. The face of the case is marked off at suitable intervals to indicate the wants of the person for whose use the signal-box is provided. One of the marks 85 indicate zero, and the index, as b', will normally point to this zero-indicating mark. When the lug b' is in this position, it will touch against the contact-piece M' of conducting material. 90

The plate B will form part of the face of the case, and the lug b' will be so arranged that when traveling it will touch the contact-point M' and circular rim M, both of conducting material. The indicator at the central 95 station or office is also inclosed in a suitable case, the face of which is marked off at proper intervals in the same manner as the faces of the signal-boxes. One of the marks indicates zero, and the index K¹⁰ will normally point to 100 this zero-indicating mark. I will now describe the mechanism of this indicator.

K K' designate a pair of spool-magnets mounted in any suitable frame and having

their cores connected in the usual manner. Between the magnets K K' is a sliding arm K², whose ends pass through holes in the portions k k' of the frame. The armature K³ is 5 fastened to this sliding arm near one end, and a spiral spring K⁴ rests against the inner side of the armature K³ at one end, while the other end rests against the inner side of the portion k' of the frame. This spiral spring 10 will be of sufficient tension to permit the armature K³ to be attracted by the magnets K K' and remove the armature from contact with the magnets when the magnets cease to 15 attract the armature. The amount of play of the armature K³ is regulated by thumb-screws k² on the portion k of the frame.

K⁵ designates an arm fastened at one end to the arm K² and at the other end to an arm K⁶. The arm K⁵ is suitably pivoted, as at k³, 20 to the frame. The free end of the arm K⁶ is held in contact with a ratchet-wheel K⁷ by a spring, as k⁴. Another arm K⁸ is fastened at one end to the frame, and its free end is held 25 in contact with the ratchet-wheel K⁷ by a spring K⁵. Both the arms K⁶ and K⁸ work in suitable guides in a portion k⁶ of the frame.

The ratchet-wheel K⁷ is mounted in any suitable manner in the frame. It has a pin k⁷ 30 fixed to it long enough to strike another pin k⁸, arranged on the frame so as to act as a stop to prevent the further rotation of the ratchet-wheel K⁷. A post K⁹ is fastened to the ratchet-wheel K⁷ to turn with it, and a coiled spring is arranged within the ratchet-wheel K⁷ to 35 cause the revolution backward of the ratchet-wheel K⁷ and post K⁹ when the arms K⁶ and K⁸ are withdrawn from contact with the ratchet-wheel K⁷. An index K¹⁰ is fastened to the post K⁹ in such manner that when the pins k⁷ 40 and k⁸ strike each other this index will point to zero on the face of the indicator.

L L' designate a second pair of spool-magnets suitably mounted in the frame and having their cores connected in the usual manner. 45 L² is the armature of these magnets. It is fastened to a rod L³, one end of which extends downwardly far enough to be able to engage the arms K⁶ and K⁸. A rod L⁴ is fastened to this rod L³ and passes through holes in the 50 frame. This rod L⁴ serves to hold the rod L³ and armature L² in place.

L⁵ designates a thumb-screw, which serves to regulate the amount of play of the rod L³ and armature L².

55 This indicator may be used in connection with indicators in ordinary use in which an electric current is used to give an alarm and indicate the number of a room.

N designates an electric battery of any suitable kind. From one of the poles of this battery a wire O extends to the magnet of an ordinary electric bell, as P, and from the magnet of this bell a wire O' extends to the magnets, as Q, of an annunciator for announcing 60 the numbers of the rooms of the house. From these magnets wires O² extend to the contact points M² of the various signal-boxes in the

rooms whose numbers the said magnets, as Q, when energized are intended to announce. From the battery N another wire R extends 70 to the magnets K K', and from these magnets a wire R' extends to a contact-piece S. A wire T extends from the battery N to the movements of the various signal-boxes.

U is another battery, from one pole of which 75 a wire V extends to the magnets J J', and from the magnets J J' a wire V' extends to the contact-piece M'. From the other pole of the battery U a wire W extends to the rim M. I may also connect the opposite poles of the 80 battery U with the magnets L L', and a push-button X may be used for closing the circuit to cause the operation of the magnets L L'.

In Fig. 9 I have shown the indicator connected with two signal-boxes, which I have 85 marked, respectively, "No. 1" and "No. 2."

I will now describe the operation of the apparatus with special reference to Fig. 9, in which two signal-boxes are shown as included in the series, premising, however, that 90 any desired number of signal-boxes may be included in the series and that the operation of the apparatus will be the same no matter how many boxes are so included. Let us suppose that we are in the room in which 95 signal-box No. 1 is placed and that we desire coal. Taking hold of the knob b, I will commence to turn the plate B and with it the lug b' in the direction indicated by the arrow. The moment the lug b' touches the contact-point M² an electric circuit is formed from the battery N along the wire T to the movement of the signal-box, from this movement through the lug b' to the contact-point M², from the contact-point M² along the wire O² through the 100 magnet Q, thence along the wire O' through the magnet of the electric bell P, along the wire O to the battery. When this circuit is established, the magnet Q will cause the number of the room to be displayed in a manner 105 well known and the bell P will ring, thereby notifying the attendant that the inmates of room No. 1 are calling. From one pole of the battery U a wire W extends to the rims M of the several signal-boxes in the series, 110 and from the other pole of the battery U a wire V extends to the magnets J J' of the several signal-boxes in the series. When the lugs b' of all the signal-boxes in the series 115 are at rest, the lugs b' rest upon their corresponding contact-pieces M', the magnets J J' in the several signal-boxes are demagnetized, and no circuit is established through them; but as I continue to move the lug b' 120 of station-box No. 1 around toward the want 125 I desire to indicate, said lug b' will come in contact with the rim M of signal-box No. 1, and an electric circuit will be formed, as follows: From the battery U along the wire W to the rim M of signal-box No. 1, from rim M of 130 that signal-box to the lug b' thereof, from said lug b' to and through the movement of signal-box No. 1, and thence along the wire Z to the movements of other signal-boxes in

the series. From the movements of these signal-boxes the current passes to the lugs b' thereof, and from these lugs it then passes to contact-pieces M' , upon which they are resting. The current then travels from the contact-pieces M' to the magnets $J J'$, with which they are connected, and from the magnets $J J'$ along the wire V back to the battery U . The magnets $J J'$ in the several station-boxes, excepting that of room No. 1, will thus be energized, and thereby caused to attract their armatures J^2 . This will force the armatures J^2 to draw down their arms J^3 , thereby pulling down the pin j^2 and raising the plate j^4 into the opening of the plate B of its signal-box, into which opening said plate j^4 is adapted to fit. Thus the plates j^4 in the various signal-boxes will lock the plates B thereof against movement, and as the plates B are thus locked and remain locked until the lug b' of station-box No. 1 ceases contact with its rim M the movements of the signal-boxes other than box No. 1 cannot be operated. The plates j^4 may have the word "Closed" on them, as shown in Fig. 1, so that the occupants of the rooms whose signal-boxes are in the series will be informed when the indicator is in use. The index b' in room No. 1 will be drawn around until it reaches the point marked "Coal." The pawl g will prevent the ratchet-wheel G from revolving while the index b' is being moved in the direction indicated by the arrow, but will allow the ratchet-wheel G to revolve in a direction opposite to that indicated by said arrow. When the index b' reaches the point marked "Coal," the knob b will be freed, the pawl d will engage with one of the teeth of the ratchet-wheel C , and as the spring I causes the shaft A to revolve backward the shaft A carries back with it the ratchet-wheel C . The ratchet-wheel C will, through the pawl d , carry back with it the toothed wheel D , and this toothed wheel D will of course cause the ratchet-wheel G and wheel H to move with it. The wheel H has, in its circumference, contact-points, the spaces between which are filled with non-conducting material. As each of the contact-points in the circumference of the wheel H touches the contact-piece S , an electric current is caused to flow from the battery N along the wire T to the movement of the signal-box, and from the movement through the contact-points in the circumference of the wheel H to the contact-piece S , thence along the wire R' , through the magnets $K K'$ of the indicator, to the wire R , and back to the battery N . It will be seen, therefore, that as each of the contact-points of the wheel H touches the contact-piece S , the magnets $K K'$ will attract their armature K^3 , thereby moving the sliding arm K^2 from which motion is transmitted through the arm K^5 to the arm K^6 . At each attraction of the armature K^3 the arm K^6 will move the ratchet-wheel K^7 forward one tooth, and this motion will be transmitted to the post K^9 and index K^{10} .

The various wants indicated on the face of the case of the signal-boxes are arranged in the same order on the face of the indicator, so that if "Coal" is arranged twenty-first in order on the signal-box it will be twenty-first in order on the indicator. If "Coal" is the twenty-first want twenty-one contact-points on the wheel H will touch the contact-piece S as the post A travels back to its initial position at zero. The magnets $K K'$ will attract the armature K^3 twenty-one times. The ratchet-wheel K^7 will be moved forward twenty-one teeth, and the index K^{10} will point to the twenty-first want on the indicator, which is "Coal." As soon as the lug b' of station No. 1 in its return leaves its rim M , the electric circuit which operated the magnets $J J'$ in the other rooms is broken, the plates j^4 will be caused to drop back by the springs j^6 , and the movements will thereby be unlocked and may be operated. When the lug b' touches the contact-piece M^2 in its return, the bell P is again caused to ring, as before explained, thereby notifying the attendant at the central station or office that the indicator shows the want of the person in room No. 1.

An ordinary electric push-button may be provided for the attendant at the office to return the index K^{10} to zero. From one pole of the battery U a wire may extend through the magnets $L L'$ to the push-button X , and from the other pole of the battery U another wire may extend to the push-button. When the attendant presses the push-button, the circuit is closed through the magnets $L L'$, and these magnets will then attract the armature L^2 . This will cause the arm L^3 to engage the arms K^6 and K^8 , and withdraw these arms from the ratchet-wheel K^7 . When this occurs, the coiled spring within the ratchet-wheel K^7 will cause the ratchet-wheel K^7 to revolve backward until the pins k^7 and k^8 strike each other. The ratchet-wheel K^7 moves back with the post K^9 and index K^{10} , so that when the pins k^7 and k^8 strike each other the index K^{10} will point to zero on the indicator. When the attendant ceases to press the push-button X , the circuit is broken and the arms K^6 and K^8 are caused by their springs to again engage the ratchet-wheel K^7 .

Instead of the above-described means for withdrawing the arms K^6 and K^8 from the ratchet-wheel K^7 the arm L^3 may be operated by mechanical means. The construction of such means is so obvious as not to require description.

What I claim as my invention, and desire to secure by Letters Patent, is—

1. The combination of a shaft, a plate, as B , fastened to said shaft, a device whereby said plate may be locked against movement, a stop for limiting the movement of said shaft, a ratchet on said shaft, a pawl mounted on a wheel and capable of engagement with said ratchet, means for regulating the speed of travel of said last-mentioned wheel, another

- wheel mounted with said last-mentioned wheel and capable of revolving with it and having electrical contact-points, means for preventing said wheel having electrical contact-points from revolving in more than one direction, and means for revolving the shaft in a direction opposite to that in which it is turned by the operator, substantially as specified. 5
- 10 2. The combination of a shaft, a plate, as B, fastened to said shaft, a stop for limiting the movement of said shaft, a ratchet on said shaft, a pawl mounted on a wheel and capable of engagement with said ratchet, 15 means for regulating the speed of travel of said last-mentioned wheel, another wheel mounted with said last-mentioned wheel and capable of revolving with it and having electrical contact-points, means for preventing 20 said wheels having electrical contact-points from revolving in more than one direction, means for revolving the shaft in a direction opposite to that in which it is turned by the operator, a magnet or magnets, an armature 25 therefor, and a device operated by said armature for locking the movements of the signal-boxes against operation, substantially as specified. 30
3. In a signal-box, the combination of an electrical contact-point, as M', upon which a contact-piece electrically connected with the movement of the box rests when the box is not being operated, a wire connecting said contact-point with a magnet or magnets, an armature for said magnet or magnets, a device operated by said armature for locking the movement of the signal-box against operation, means for establishing electrical communication between said contact-points and 40 the said contact-piece electrically connected with the movement of the signal-box to magnetize said magnet or magnets to lock the movement of the signal-box against operation, and a contact-point, as M², within reach of said contact-piece electrically connected to the movement of the signal-box, a wire connecting said contact-point, as M², with an apparatus at a central office for indicating when said contact-piece electrically connected with 45 the movement of the signal-box and said contact-point, as M², touch each other, and means for establishing electrical communication between said contact-piece and point to operate said central-office apparatus, substantially as specified. 50
- 55 4. In a signal-box, the combination of a contact-piece electrically connected with the movement of the box, a contact-point, as M', upon which said contact-piece rests when the box is not being operated, a wire connecting said contact-point, as M', with a magnet or magnets, an armature for said magnet or magnets, a device operated by said armature for locking the movement of the signal-box against operation, a contact-point, as M², within reach of said contact-piece electrically connected to the movement of the box, a wire 60 connected with said contact-piece, as M², a case inclosing the movement of the box and having its face suitably marked, an index secured to the movement of the box, a contact-piece, as M, within reach of said contact-piece electrically connected to the movement of the signal-box, and a wire connected to said contact-piece, as M, substantially as specified. 70
- 75 5. In a signal-box, the combination of an electrical contact-point, means for connecting said contact-point with a magnet or magnets, an armature for said magnet or magnets, a device operated by said armature for locking the movement of the signal-box against operation when said magnet or magnets are energized, means for unlocking the movement of the signal-box upon the demagnetization of said magnet or magnets, a contact-piece 80 electrically connected to the movement of the signal-box and resting on said contact-point when the box is not being operated, a second contact-piece, as M, connected with the box movement while it is running, and a source 85 of electricity, one pole of which is connected with the contact-point upon which the contact-piece electrically connected to the movement of the signal rests when the box is not being operated, and the other pole of which 90 is connected with said contact-piece, as M, substantially as specified. 95
6. The combination of a magnet or magnets, as K K', an armature, as K³, means, as K⁴, for normally holding said armature out of contact with its magnet or magnets, an arm, as K², connected to another arm, as K⁵, an arm, as K⁶, connected to said arm, as K⁵, means, as K⁷, for holding one end of the arm K⁶ in contact with a ratchet-wheel, as K⁷, another arm, as K⁸, means, as K⁹, for holding one end of the arm, as K⁸, in contact with the ratchet-wheel, as K⁷, a post, as K⁹, revolved by said ratchet-wheel, an index affixed to said post, means for causing said ratchet-wheel to revolve 100 backward when said arms, as K⁶ and K⁸, are withdrawn from contact with it, and means for establishing electrical communication between said magnets, as K K', and an operating-station, substantially as specified. 105
- 110 7. The combination of a shaft, as A, a plate, as B, fastened to said shaft, a stop for limiting the movement of said shaft, a ratchet on said shaft, a pawl mounted on a wheel and capable of engagement with said ratchet, 115 means for regulating the speed of travel of said last-mentioned wheel, another wheel fastened to said last-mentioned wheel and capable of revolving with it and having electrical contact-points, a contact-piece, as S, means 120 for preventing said wheel having electrical contact-points from revolving in more than one direction, means for revolving the shaft in a direction opposite to that in which it is turned by the operator, a wire connecting the 125 contact-piece, as S, with a magnet or magnets, as K K', an armature, as K³, means, as K⁴, for normally holding said armature out of engagement with its magnet or magnets, an arm, 130

as K^2 , connected to another arm, as K^5 , an arm, as K^6 , connected to said arm, as K^5 , means, as k^4 , for holding one end of the arm, as K^6 , in contact with the ratchet-wheel, as K^7 , another arm, as K^8 , means, as k^5 , for holding one end of the arm, as K^8 , in contact with the ratchet-wheel, as K^7 , a post, as K^9 , an index affixed to said post, means for causing said ratchet-wheel, as K^7 , to revolve backward 10 when said arms, as $K^6 K^8$, are withdrawn from contact with it, and a source of electricity, one pole of which is connected to the magnets, as $K K'$, and the other pole of which is connected to the movement of the signal-box, 15 whereby when the contact-piece, as S , touches the contact-points of the wheel, as H , said magnets, as $K K'$, will be energized to operate their armature, substantially as specified.

8. A signaling system comprising signal-boxes having time-trains, a conductor connecting said time-trains with each other, wheels, as H , in said time-trains, contact-pieces, as S , in proximity to said wheels, as H , a conductor connecting said contact-pieces, 25 as S , with each other, a source of electricity, one pole of which is connected with the conductor that connects the time-trains with each other and the other pole of which is connected with the conductor that connects the 30 contact-pieces, as S , with each other, a magnet or magnets at a central station or office in the circuit which comprises the said time-trains and contact-pieces, as S , an armature for said magnet or magnets, means for normally holding said armature out of engagement with its magnet or magnets, and arms operated by said armature to cause the movement of an index, substantially as specified.

9. The combination, with a receiving-station, of a series of signal-boxes for use in connection therewith, the movements of said boxes being electrically connected with each other, a contact-point, as M' , arranged on each signal-box, upon which a contact-piece electrically connected with the movement of such signal-box normally rests, a wire leading from said contact-points to a magnet or magnets, an armature for the same, means operated by said armature to lock the movement of the 45 signal-box against operation when its magnet or magnets is energized, the said magnet or magnets of the signal-boxes in the series being electrically connected with each other and with one pole of a source of electricity, a contact-piece, as M , arranged on each signal-box, upon which the aforesaid contact-piece, which is electrically connected with the movement of the signal-box, may rest while the movement of said signal-box is being operated, said contact-piece, as M , being connected with the 50 opposite pole of said source of electricity, whereby when said contact-piece in electrical communication with the movement of one of the signal-boxes of the series rests upon the said contact-piece, as M , the electric circuit will be closed and the magnets of the other signal-boxes in the series will attract their armatures and lock the movements of such signal-boxes against operation, a contact-point, as M^2 , arranged on each signal-box within reach of the contact-piece of said signal-box, which is electrically connected to the movement thereof, a wire leading from each of said contact-points, as M^2 , to an apparatus at a central station for indicating the 55 60 65 70 75 80 85 90 95 100 105 110 115 120 125 130 135

ries will attract their armatures to lock the movements of such signal-boxes against operation, a contact-point, as M^2 , arranged on each signal-box within reach of the contact-piece of said signal-box, which is electrically connected to the movement thereof, a wire leading from each of said contact-points, as M^2 , to an apparatus at a central station for indicating the box on which the contact-point, which is connected with such indicator, is arranged, and a source of electricity, one pole of which is connected to said indicating apparatus and the other pole of which is connected to the movements of all the signal-boxes in the series, substantially as specified. 10. The combination, with a receiving-station, of a series of signal-boxes for use in connection therewith, the movements of said boxes being electrically connected with each other, a contact-point arranged in each signal-box, upon which a contact-piece electrically connected with the movement of such signal-box rests while said signal-box is not being operated, a wire leading from said contact-points to a magnet or magnets, an armature for the same, means operated by said armature to lock the movement of the signal-box against operation when its magnet or magnets are energized, the said magnet or magnets of the signal-boxes in the series being electrically connected with each other and with one pole of a source of electricity, a contact-piece, as M , arranged on each signal-box, upon which the aforesaid contact-piece, which is electrically connected with the movement of the signal-box, may rest while the movement of said signal-box is being operated, said contact-piece, as M , being connected with the opposite pole of said source of electricity, whereby when said contact-piece in electrical communication with the movement of one of the signal-boxes of the series rests upon the said contact-piece, as M , the electric circuit will be closed and the magnets of the other signal-boxes in the series will attract their armatures and lock the movements of such signal-boxes against operation, a contact-point, as M^2 , arranged on each signal-box within reach of the contact-piece of said signal-box, which is electrically connected to the movement thereof, a wire leading from each of said contact-points, as M^2 , to an apparatus at a central station for indicating the box on which the contact-point which is connected with such indicator is arranged, a contact-piece, as S , arranged on each signal-box in the series, all said contact-pieces, as S , being electrically connected to each other, a wheel, as H , in each signal-box in the series, means for regulating the speed of travel of said wheel, as H , a magnet or magnets at a central station electrically connected to the said contact-pieces, as S , an armature for the said magnet or magnets, arms operated by said armature to cause the movement of an index, and a source of electricity, to one pole of which is connected the wire which connects the contact-pieces, as S , with each other.

nects the movements of all the signal-boxes in the series and to the other pole of which is connected the wires leading from the contact-pieces S, and the apparatus which indicates the box which is being operated, substantially as specified.

11. The combination, with a receiving-station, of a series of signal-boxes for use in connection therewith, the movements of said boxes being electrically connected with each other, a contact-point arranged on each signal-box, upon which a contact-piece electrically connected with the movement of such signal-box normally rests, a wire leading from said contact-points to a magnet or magnets, an armature for said magnet or magnets, means operated by said armature to lock the movement of the signal-box against operation when its magnet or magnets are energized, the said magnet or magnets of the signal-boxes in the series being electrically connected with each other and with one pole of a source of

electricity, and a contact-piece, as M, arranged on each signal-box upon which the aforesaid contact-piece, which is electrically connected with the movement of the station-box, may rest while the movement of such signal-box is being operated, said contact-piece, as M, being connected with the opposite pole of said source of electricity, whereby when the said contact-piece in electrical communication with the movement of one of the signal-boxes of the series rests upon said contact-piece, as M, the electric circuit will be closed and the magnets of the other signal-boxes in the series will attract their armatures and lock the movements of such signal-boxes against operation, substantially as specified.

ABRAHAM NEWMAN.
